POINTING DEVICE FOR ORDNANCE.

1,368,458.

Specification of Letters Patent. Patented Feb. 15, 1921.

Application filed September 3, 1920. Serial No. 408,100.

To all whom it may concern:

Be it known that I, RICHARD SCHÜRMANN, residing at Essen, Germany, a citizen of the German Republic, have invented a certain 5 new and useful Improvement in Pointing Devices for Ordnance, of which the following is a specification.

This invention relates to pointing devices for ordnance, in which the gun barrel can 10 be rotated about the axis of the trunnions independently of the two parts of the sighting device, which can be rotated relatively to each other to correspond to the firing angle and can be adjusted by means of adjustment marks in a definite angular position 15 with respect to one of these parts. The invention refers to a pointing device of this kind, in which all the parts, which determine the elevation of the gun barrel are so 20 combined, that they can be separated from the gun as a whole in an easily detachable manner.

The invention will be described with reference to the accompanying drawings in 25 which—

Figure 1 is a section taken at right angles to the plane of elevation of those parts of the pointing device concerned.

Fig. 2 is a side elevation corresponding 30 to Fig. 1, looking from the left, and

Fig. 3 is a section on the line 3—3 of Fig. 1 looking from the left.

The gun barrel (not shown) rotates relatively to the carriage B about the axis of the 35 two trunnions, of which only one, A, is shown in the drawings. The journal A of the trunnion shown has a cylindrical extension A¹, which is surrounded by a hollow journal b² arranged on the frame B¹ of the 40 sighting device. The frame B¹ is rigidly connected to the gun carriage in an easily detachable manner by a screw nut a² which is fixed on a screw-threaded part of the extension A¹ and by means of a bolt C, passed 45 through two eyes b³ on the gun carriage. On the hollow journal b² is pivotally mounted a sleeve D, which carries a sighting telescope D¹.

The sleeve D is provided with a series of 50 teeth d², with which a worm E mounted in the frame B¹ gears, so that, by rotating the worm, the sighting line of the telescope D¹ can be adjusted in the direction of the elevation of the gun. On the hollow journal 55 b² is also pivotally mounted a sleeve F,

which is surrounded by the sleeve D and is coupled by a pin f² to a sleeve F¹ likewise mounted on the hollow sleeve b² and lying outside the sleeve D. The sleeve F¹ has a series of teeth f³, with which a worm G 60 mounted on the sleeve D gears. The sleeve D, which carries the sighting telescope D¹ and the double sleeve F F¹, which can be rotated by the worm gearing f³ G relatively thereto as a whole form the two parts 65 of the sighting device, which can be rotated relatively to each other to correspond to the attachment angle, or proper inclination corresponding to the desired range.

The range corresponding to the attachment angle is read off by means of a graduation f⁵ arranged on a projection f⁴ on the sleeve F (see Fig. 2) together with the mark d⁴ on the edge of a window d³ provided in the sleeve B for the purpose of rendering 70 the graduation f⁵ visible. Finally there is mounted on the hollow journal b² another sleeve H, which can be rotated independently of the sleeves D and F F¹ and is prevented from moving axially by a ring b⁴ screwed 80 on to the hollow journal b². On the sleeve H is mounted a pointer H¹, the free end of which is provided with an adjusting mark h² (see Figs. 2 and 3) and which is coupled to the journal A by a lug h³ on it which 85 lug engages in a corresponding recess a⁴ in a coupling piece a³ rigidly attached to the journal A.

On the sleeve F¹ is mounted a second pointer f⁶, which carries a mark f⁷, which 90 can be adjusted to the mark h² on the pointer H¹ (see Figs. 2 and 3). When the sleeve F F¹ is adjusted by turning the worm G, so that the mark d⁴ (see Fig. 2) points to the zero point of the graduation f⁵ and 95 at the same time the sleeve D is rotated by the worm E into an angular position in which the sighting line of the telescope D¹ is parallel with the plane through the axis of the journal A parallel with the longitudinal 100 axis of the gun barrel, the adjusting marks f⁷ and h² are situated exactly opposite each other.

In order to elevate the gun on a target, the sleeve D is first brought by the worm gearing E d² into an angular position, in which the sighting line of the telescope D¹ points on the target and the sleeve F F¹ with the pointer f⁶ is so adjusted by the worm gearing G f³, that the division mark of the grad- 110

uation f^6 , corresponding to the desired range, is opposite the mark d^4 . Finally an elevation is imparted to the gun barrel by means of the elevating gear, so that the mark h^2 5 of the pointer H^1 , which is in consequence of its being coupled by the lug h^3 to the member A, which executes the same rotary movement as the gun barrel, likewise takes part in the movement of this latter, is brought 10 into a position in which it is opposite the mark f^7 . The gun is then pointed for elevation on the target.

After the removal of the screw nut a^2 and the bolt C, the frame B^1 with the hollow 15 journal b^2 and all the parts of the pointing device mounted thereon can be separated from the gun carriage by pushing it in the direction of the axis of the journal A, all the parts determining the elevation namely the 20 sighting device and the member H H^1 remaining thereby combined.

Claims:

1. In a device of the class described the combination with an independently rotatable gun, and horizontal trunnions, of a sighting device, said sighting device comprising two parts which are adjustable relatively to one another, and a coöperating pointer mounted on a gun trunnion and rotatable 30 therewith, substantially as and for the purpose set forth.

2. A pointing device for ordnance adapted to be positioned upon the gun trunnion, said pointing device comprising a hollow journal 35 mounted upon said trunnion, a telescope supporting sleeve rotatably mounted on said journal, a telescope supported by said sleeve, means for rotating said sleeve, a pair of additional sleeves mounted on said journal, a 40 pointer carried by said second sleeves, a second pointer mounted to rotate with said trunnion, means for independently operating said second pair of sleeves, substantially as and for the purpose set forth.

45 3. A detachable pointing device for ordnance comprising a hollow journal adapted to be supported upon the trunnion of the gun support, a sighting telescope, a sleeve rotatably mounted on said journal for supporting said sighting telescope, a pair of second sleeves connected to rotate simultaneously upon said journal, said pair of sleeves coöperating with said telescope supporting sleeve for indicating the range, 50 means for independently rotating said telescope supporting sleeve and said pair of sleeves, a pointer-carrying sleeve rotatably mounted upon said journal, means for operatively connecting said pointer sleeve to said trunnion, said means comprising a stud on said pointer sleeve, a coupling-piece on 55 said trunnion and removable means for retaining said journal on the trunnion, substantially as described.

60 65 4. A pointing device for ordnance com-

prising a gun carriage and a gun barrel having a trunnion rotatably mounted on the gun carriage and positively connected to the gun barrel for rotary movement therewith, said pointing device comprising a sighting means carrier, a detachable frame rigidly connected to the gun carriage, a rotatable member mounted on said frame coaxially with said trunnion and being positively connected to said sighting means carrier, a second rotatable member mounted on said frame coaxially with said trunnion, means for adjusting said two rotatable members relatively to each other according to the firing angle of the gun, a third rotatable member coaxial with said trunnion, also mounted on said frame, a clutch adapted to be thrown out of action for coupling said third rotatable member to said trunnion, and means fixing a particular angular position 70 of said second and third rotatable members with respect to each other, said fixing means comprising two adjusting marks registering with each other when said second and third rotatable members assume their particular angular position with respect to each other. 75

5. A pointing device for ordnance comprising a gun carriage and a gun barrel having a trunnion rotatably mounted on the 95 gun carriage and positively connected to the gun barrel for rotary movement therewith, said pointing device comprising a sighting means carrier, a detachable frame rigidly connected to the gun carriage, said frame 100 having a hollow journal coaxially mounted on said trunnion, a rotatable member coaxially mounted on said hollow journal, and being positively connected to said sighting means carrier, a second rotatable member 105 coaxially mounted on said hollow journal, means for adjusting said two rotatable members relatively to each other according to the firing angle of the gun, a third rotatable member also coaxially mounted on 110 said hollow journal, a clutch adapted to be thrown out of action for coupling said third rotatable member to said trunnion, and means fixing a particular angular position 115 of said second and third rotatable members with respect to each other, said fixing means comprising two adjusting marks registering with each other when said second and third rotatable members assume their particular angular position with respect to each other. 120

6. A pointing device for ordnance comprising a gun carriage and a gun barrel having a trunnion rotatably mounted on the gun carriage and positively connected to the gun barrel for rotary movement therewith, said pointing device comprising a sighting means carrier, a detachable frame rigidly connected to the gun carriage, a rotatable member mounted on said frame coaxially with said trunnion and being posi- 125 130

tively connected to said sighting means carrier, a second rotatable member mounted on said frame coaxially with said trunnion, means for adjusting said two rotatable members relatively to each other according to the firing angle of the gun, a third rotatable member coaxial with said trunnion, also mounted on said frame, a clutch adapted to be thrown out of action for coupling said 10 third rotatable member to said trunnion, an arm arranged on said second rotatable mem-

ber and another arm arranged on said third rotatable member, said arms carrying adjusting marks adapted to register with each other.

15

The foregoing specification signed at Essen, Germany, this 27th day of May, 1920.

SCHÜRMANN.
